UNITED STATES PATENT OFFICE.

MILLARD GILMORE, OF OAK PARK, ILLINOIS.

OPERATING MECHANISM FOR SHUTTER-DOORS, ETC.

Application filed January 3, 1922. Serial No. 526,817.

This invention relates particularly to shutter-doors, or shutter-curtains, and the operating means therefor; and the primary object is to provide improved mechanism for controlling the movements of a fire-door, or fire-curtain, of the vertical lift type, and especially the well known shutter-door type.

The invention is illustrated in its preferred embodiment in the accompanying drawings, in which—

Figure 1 represents a view mainly in elevation, but partly in section, showing a shutter-door and its operating mechanism constructed in accordance with the invention; Figure 2, a broken vertical sectional view taken as indicated at line 2 of Fig. 1; Figure 3, a broken sectional view taken as indicated at line 3 of Fig. 1; Figure 4, a view, diagrammatic in its nature, showing the electric circuits of the solenoids and brake device employed; Figure 5, a view of a dial employed for indicating the position of the plungers of the solenoids; and Figure 6, a broken sectional view showing a modification of the invention.

In the embodiment illustrated in Figs. 1 to 5 inclusive, A represents a wall provided with a door-opening, or window-opening, A'; B, a hood mounted on the wall above the door-opening; C, a shaft journaled in said hood and having a projecting end equipped with a rigidly-secured sheave, or winding-drum C'; D, a drum journaled on said shaft; E, a torsion spring located in said drum and connected at one end with the shaft and at the other end with the drum; F, a shutter-door, or shutter-curtain mounted on the drum; and G, electro-magnetic means controlling the operation of the shutter-door.

The hood B is shown provided with bearings 1 for the shaft C. The drum D is provided at one end with a rigidly secured plug 2 which has a central perforation journaled on the shaft. One end of the spring E is connected, as indicated at 2^a, with the plug or end wall 2 of the drum. The other end of the spring is connected, as indicated at 3, with a collar 3^a secured on the shaft.

The shutter-curtain or door F is of the usual construction. It has one end secured to the drum D and is adapted to be rolled upon the drum. The shutter passes through a guide B' which is provided with a stop, as indicated at 4, for the lowermost slat of the shutter.

The electro-magnetic mechanism G which controls the movements of the drum and shutter comprises solenoids G' and G², the former being adapted to elevate the shutter, and the latter being adapted to lower the shutter. Also, the mechanism includes an electro-magnetically-released brake G³. The solenoid G' is provided with a magnetic core, or plunger 5 which is connected by a cable 5^a with the winding drum C', the cable being suitably attached to the drum. Also, the solenoid G² is provided with a magnetic core or plunger 6 which is connected by a cable 6^a with the winding drum C', the cable being suitably attached to the drum. The lower ends of the cores 5 and 6 are equipped with non-magnetic guide rods, such as brass rods, 7, which work through guides in a stationary member 8. A stop 9 serves to limit the upward movement of the cores. The guide rod of the core 5 has attached to its lower end a weight 5^b which supplements the weight of the core. The core 5 and the added weight 5^b are sufficient to overbalance the core 6 and to give to the torsion spring E a sufficient tension to counterbalance approximately the shutter F when it is in its elevated position.

The magnetic brake G³ comprises a disk 10 which is secured on the shaft C; brake members 11 adapted to grip the disk 10, said brake members being held in the gripping position by a spring 12; and a solenoid 13 acting upon lever arms 11^a of the brake and adapted to release the brake.

The circuit for the three solenoids mentioned comprises the main wires 14 and 15, energized from any suitable source, such as a battery 16. The wire 14 is connected, through branches 14^a, with the windings of the solenoids G' and G². From the other end of the solenoid windings, wires 14^b lead to switch points 17 and 18. Coacting with the switch points 17 and 18 are switches 17^a and 18^a which are connected with a wire 19 which leads to the winding of the solenoid 13. With the other end of the winding of the solenoid 13 is connected the wire 15.

From the foregoing, it appears that the brake G³ normally locks the shaft C. When either of the switches 17^a or 18^a is closed, the brake is released by the solenoid 13, so that when either of the solenoids G' or G² is operated, the brake is automatically released to permit such operation.

The operation of the mechanism is as follows. Normally, the plunger 5 with the ad-

ditional weight 5^b holds the shutter in the elevated or open position, by holding the shaft C turned to such a position as to place an initial tension on the torsion spring E. By closing the switch 17^a, the shaft C is turned in the direction indicated by the arrow in Fig. 4, thus releasing some of the tension of the torsion spring. This disturbs the balance of the rolling shutter, and the weight of the depending portion of the shutter causes the shutter to descend to close the door-opening. This action may be obtained by a comparatively small movement of the plungers of the solenoids, as a comparatively small loosening of the tension of the spring permits the curtain to descend. By closing the switch 18^a, the solenoid G' is operated which winds the spring up sufficiently to cause it to turn the drum and elevate the curtain. The switches 17^a and 18^a are normally thrown open by springs 17^b and 18^b. It will be understood that the circuits of the several solenoids may be arranged as may be desired. Also, it will be understood that the electro-magnetic mechanism may be varied otherwise, if desired. For example, the solenoid G² which serves to lower the curtain may be omitted. This may be accomplished, for example, by cutting out the winding of the solenoid G² by extending a wire 20 to form a short circuit past the winding of the solenoid. The wire 20 is indicated in dotted lines in Fig. 4. With this modified arrangement, when the switch 17^a is closed, the brake is released without affecting the solenoid G'. This permits the torsion spring E to turn the shaft C in a direction to unwind the spring sufficiently to disturb the balance and permit the shutter to descend to the closed position. The shutter may be elevated to the open position by closing the switch 18^a which causes the solenoids 13 and G' to be energized, thus releasing the brake and causing the shaft C to be turned in a direction to wind up the spring sufficiently to elevate the curtain. Obviously, by manipulating the switches in a simple manner, the door may be stopped in a partially open position, if desired. The solenoids G' and G² are located in a suitable casing 21. This casing may be provided with an opening equipped with a transparent cover plate 22; and the plungers 5 and 6 may be equipped with pointers 5^c and 6^c; so that the position of the plungers may be noted with reference to an indicator-line 23, as shown in Fig. 5.

In the modification shown in Fig. 6, D' represents the drum; E' the torsion spring; C² the shaft; and F' the shutter-curtain. In this case, the shaft is equipped at one end with a wheel 24 which is engaged by a catch 25 in accordance with the known practice, the shaft being thus held in position to place the spring E' under sufficient torsion

to hold the shutter in elevated condition. The drum D' is equipped at its other end with a hollow shaft D² upon which is secured a winding drum D³. A pair of solenoids G⁴ and G⁵, equipped with plungers 26, serve to operate the drum D'. The plungers 26 are connected by cables 26^a with the drum 23. Thus, by operating one of the solenoids, the drum may be turned to lower the curtain, and by operating the other solenoid, the drum may be turned to raise the curtain.

The preferred embodiment of the invention, however, is one in which the solenoid or solenoids operate to wind or unwind the torsion spring through the medium of the shaft C.

In case of fire, it is desirable to employ means associated with the electro-magnetic shutter-operating means, for causing the shutter to be automatically closed. In the illustration given, a weight H is employed which, in case of fire, is adapted to release the grip of the brake device G³ and permit the shaft C to turn and release the tension of the torsion spring D, so that the shutter will be permitted to drop. The weight H is held in elevated position by a trigger H' controlled by a fuse-link H². In case of fire, the fuse-link is melted, releasing the trigger and thereby permitting the weight H to fall. The weight H is attached to a chain H³ which is connected with an arm 11^a of the brake device, so that when the weight falls, it will effect release of the brake. The chain H³ should, in practice, be short enough to effect release of the brake before the weight can strike the upper end of the plunger 6, which, it will be understood, is in elevated position when the shutter is in elevated position.

In practice the controlling switches may be located at any convenient position; and by suitably manipulating the switches, the door may be closed completely, may be opened completely, or may be stopped at an intermediate position.

Obviously, the improved curtain-operating means may be employed to actuate or control the position of any kind of a curtain, or flexible shade which is adapted to roll up, as, for example, a window shade, an awning or the like, which is adapted to be rolled up or lowered in a manner analogous to a fire-curtain.

It may be added that in the case of a properly counterbalanced, freely moving shutter, a turn, or less, of the shaft is sufficient to so change the tension of the spring as to raise or lower the shutter, as the case may be. Moreover, since the spring approximately counterbalances the shutter in any position, it is obvious that the shutter may be operated by hand, if desired, without releasing the brake.

The foregoing detailed description has been given for clearness of understanding only, and no unnecessary limitations should be understood therefrom, but the appended 5 claims should be construed as broadly as permissible in view of the prior art.

What I regard as new, and desire to secure by Letters Patent, is:

1. In means of the character set forth, the combination of a revoluble drum, a curtain mounted thereon, a shaft extending into said drum, a torsion spring connecting said shaft and drum, a releasable brake device for said shaft serving to hold said spring normally 10 under counterbalancing tension, a cable connected with said shaft, and an electro-magnetic device for turning said shaft through the medium of said cable and thus varying the tension of said spring.
2. In means of the character set forth, the combination of a revoluble drum, a shutter-curtain mounted thereon, a shaft extending into said drum, a torsion spring connecting the shaft and drum, a cable serving to turn 15 said shaft to vary the tension of said spring, a pair of solenoids provided with cores secured to the ends of said cable, and circuit-controlling means connected with the circuits of said solenoids.
3. In means of the character set forth, the combination of a drum, a shutter-curtain mounted thereon, a shaft journaled in said drum, a torsion spring connecting said shaft and drum, a cable having an intermediate 20 portion adapted to turn said shaft, an electro-magnet having a movable member connected with one end of said cable and serving to turn the shaft to relieve the spring tension, another electro-magnet having a 25 movable member connected with the other end of said cable, means being associated therewith for holding said spring under normal tension to hold the shutter-curtain in elevated position, and circuit-controlling 30 means adapted to cause either of the electro-magnets to operate said shaft at will.
4. In means of the character set forth, the combination of a drum, a shutter-curtain mounted thereon, a shaft journalled in said drum, a spring connecting said shaft and drum, and means controlling the movements 35 of said drum, including an electro-magnetic device for actuating said shaft, an electro-magnetically controlled brake for said shaft, and a fuse-controlled device adapted to effect 40 automatic lowering of said shutter-curtain.
5. In means of the character set forth, the combination of a drum, a shutter-curtain mounted thereon, a shaft journalled in said drum, a spring connecting said shaft and drum, means controlling the movements of 45 said drum, including electro-magnetic devices for varying the tension of said spring and actuating the drum and associated

means for holding said spring under initial tension, and a fuse-controlled device adapted to automatically lower the shutter-curtain.

6. In means of the character set forth, the combination of a drum, a shutter-curtain mounted thereon, a shaft journaled in said drum, a spring connecting said shaft and drum, means controlling the movements of said drum including a cable adapted to turn 75 said shaft and thereby vary the tension of said spring, solenoids having cores connected with the ends of said cables, one of the cores being provided with means for placing said spring under initial tension to hold the shutter in elevated position, circuit-controlling means adapted to cause either solenoid to be energized, and a fuse-controlled weight adapted to disturb the balance and cause automatic lowering of said shutter. 85

7. In means of the character set forth, the combination of a drum, a shutter-curtain mounted thereon, a shaft journaled in said drum, a torsion spring connecting said shaft and drum, electro-magnetic means provided with plungers for actuating said drum, and an electro-magnetically-controlled brake adapted to control the movements of said drum. 90

8. In means of the character set forth, the combination of a drum, a shutter-curtain mounted thereon, a shaft journaled in said drum, a torsion spring connecting said shaft and drum, a solenoid provided with a movable core, a cable connecting said core with 95 said shaft, a normally set brake serving to hold said shaft, an electro-magnet adapted to release said brake, and a circuit common to said solenoid and said electro-magnet provided with circuit-controlling means, 100 whereby when the solenoid is energized the brake is released. 105

9. In means of the character set forth, the combination of a drum, a shutter curtain mounted thereon, a shaft journaled in said 110 drum, a torsion spring connecting said shaft and drum, a pair of solenoids equipped with movable cores, cables connecting said cores with said shaft and adapted to actuate the shaft in either direction, a normally set brake, an electro-magnet adapted to release said brake, and a circuit common to said solenoids and said electro-magnet and equipped with two circuit-controlling devices, each of said circuit-controlling devices controlling the circuit of one solenoid and the circuit of said electro-magnet. 115

10. In means of the character set forth, the combination of a drum, a shutter-curtain mounted thereon, a shaft journaled in said drum, a torsion spring connecting said shaft and drum, a normally set brake holding said shaft in position to place said spring under initial tension to hold the shutter in elevated position, an electro-mag- 125 130

net adapted to release said brake, a solenoid provided with a core connected by a cable with said shaft, said solenoid being adapted to turn the shaft in a direction to increase 5 the turn of the spring and elevate the shutter, and an electric circuit common to said solenoid and said electro-magnet, said circuit having one switch adapted to cause the electro-magnet only to be energized and 10 having another switch adapted to cause both the electro-magnet and the solenoid to be energized.

11. In means of the character set forth, the combination of a drum, a shutter-curtain mounted thereon, a shaft journaled in 15 said drum, a spring connecting said shaft and drum, and means controlling the movements of said drum, including an electric device for actuating the shaft to vary the 20 tension of said spring and associated automatically releasable means for holding said spring under initial tension.

12. In means of the character set forth,

the combination of a drum, a shutter-curtain mounted thereon, a shaft journaled in 25 said drum, a torsion spring connecting said shaft and drum, an electric device adapted to actuate said shaft and vary the tension of said spring, a brake adapted to control 30 the movements of said shaft, an electro-magnet controlling said brake, and circuits for said electric device and said electro-magnet having a common controlling switch.

13. In means of the character set forth, the combination of a drum, a shutter-curtain mounted thereon, a shaft journaled in 35 said drum, a torsion spring connecting said shaft and drum, an electric device for actuating said shaft and varying the tension of said spring, a normally set brake serving to hold said shaft, an electro-magnet adapted 40 to release said brake, and a circuit common to said solenoid and said electro-magnet provided with circuit-controlling means.

MILLARD GILMORE.
